CLAIM

The ornamental design for a crib as shown and described.

DESCRIPTION

FIG. 1 is a front elevational view of a crib showing my new design;

FIG. 2 is a rear elevational view thereof;

FIG. 3 is a left side view thereof;

FIG. 4 is a right side view thereof;

FIG. 5 is a perspective view thereof; and,

FIG. 6 is a second perspective view thereof.

The broken lines illustrate portions of the crib that do not form part of the claimed design.
